[57] **CLAIM**

The ornamental design of a clock housing, as shown and described.

DESCRIPTION

FIG. 1 is a perspective view of a clock housing mounted in an enclosure which has two doors with transparent faces that pivot with respect to a central frame member, wherein clock hands are shown in dashed lines;

FIG. 2 is a front view of the clock housing, as shown in FIG. 1;

FIG. 3 is a rear view of the clock housing, wherein a housing for a clock timing mechanism is shown in dashed lines, as shown in FIG. 1;

FIG. 4 is a side view of the clock housing, as shown in FIG. 1;

FIG. 5 is a side view, opposite the side view shown in FIG. 4, of the clock housing, as shown in FIG. 1;

FIG. 6 is a top view of the clock housing, as shown in FIG. 1; and,

FIG. 7 is a bottom view of the clock housing, as shown in FIG. 1.

The broken line showings of clock mechanisms are for illustrative purposes only and form no part of the claimed design.
